UNITED STATES PATENT OFFICE.

CARL G. HARWIG, OF CHICAGO, ILLINOIS, ASSIGNOR TO THE REGAN SAFETY DEVICES COMPANY, INC., OF NEW YORK, N. Y., A CORPORATION OF NEW YORK.

RELAY.

Application filed November 16, 1922. Serial No. 601,385.

This invention relates to a relay, and has particular reference to the provision of a relay designed especially for use in train control systems, as for example in the train control system forming the subject matter of the c o p e n d i n g application of A. G. Shaver, Serial No. 506,595, of Oct. 10, 1921.

A prime desideratum of my present invention comprehends the provision of a relay capable of positive and rapid operation for producing circuit changes in train control mechanism. In the train control systems to which the present invention has particular applicability, train control mechanism is provided on a vehicle of the train, and is constructed so as to be influenced automatically by mechanism located along the roadside, the latter mechanism being controlled by roadside conditions and being operative for impressing such conditions on the train, to produce a corresponding effect therein. According to one type of train control system, the roadside mechanism comprises means placed at intervals along the track for operating upon a train carried mechanism intermittently as the train moves over the roadbed. In this intermittent type of train control system when the train carried mechanism moves at intervals into cooperative relation with the roadside operating mechanism, the latter transmits a roadside condition to the vehicle carried mechanism; and translating means forming part of the vehicle carried mechanism is provided for translating such condition to produce a given train control effect, as for example for effecting the operation of brake setting elements to apply the brakes of the train. The translating means usually comprises a relay located in a circuit directly controlled by the roadside mechanism, the said relay operating to affect other train carried circuits which govern the operation of the brake setting means. In these intermittent train control systems the period of co-operation between the roadside mechanism and the train control mechanism is comparatively short, and when the train is moving at relatively high speeds, as is usually the case, this period is very brief. The relay, therefore, which acts as the means for translating the roadside conditions to the vehicle, must be constructed so as to respond with rapidity and surety to the operation of the roadside mechanism within a brief period of activity of the latter, the reliability of the entire train

control system being largely dependent upon this quick and positive behaviour of the translating relay.

In the designing of a relay which possesses the desired positiveness and rapidity of action to meet the service demands in these train control systems, it is requisite that the moving element of the relay such as the armature possess little inertia and be so mounted and supported as to respond sensitively and quickly to changes in the magnetic field of the relay which are sudden and of short duration corresponding to the changes produced by the brief period of cooperation between the vehicle carried mechanism and the roadside mechanism of the system. Another factor in producing a relay having the desired action resides in the necessity of providing a field magnetic circuit which has little reluctance so that the magnetic field produced is correspondingly strong and of sufficient strength to cause the armature to respond rapidly and unmistakably to the action thereof, with the armature and the field so inter-related as to provide a construction capable of positively controlling movable electrical contact means governing the vehicle circuits. To produce a relay in which these constructional and operative characteristics are present in a high degree is a principal object of my present invention.

The principal objects of my present invention may be said to include, besides the provision of a relay having the characteristics and capable of producing the results above referred to; the further provision of a relay in which the armature comprises a coil movable to active and inactive positions, the said coil being so constructed as to possess little inertia and being so mounted as to be very sensitive in operation, the said coil being movable in a magnetic field produced by a magnetic circuit of very low reluctance, with the construction such that the coil alone comprises the movable element, the whole magnetic circuit being formed of stationary elements, an exceeding strong field and a very light-moving armature being thus combined; the further provision of a relay of this nature in which the coil is arranged in the magnetic field so as to be movable from an inactive to a plurality of active positions therein, depending upon the selective energization of the coil; the still further provision of a relay of this nature in which the armature coil is

105

100

105

110

normally held in a neutral or inactive position by means of contact elements actuated by motion of the armature coil to its active positions; and the further provision of a relay 5 in which the parts are so interrelated and associated as to provide an inexpensive, efficient, strong and quickly assemblable construction.

To the accomplishment of the foregoing 10 and such other objects as may hereinafter appear, my invention consists in the elements and their relation one to the other, as herein-after more particularly described and sought to be defined in the claims; reference being 15 had to the accompanying drawing which shows preferred embodiments of my invention, and in which:

Fig. 1 is a front elevational view of my relay with parts shown in cross-section,

Fig. 2 is an elevational view thereof taken 20 in cross-section on the line 2—2, Fig. 1,

Fig. 3 is a plan view thereof shown on a reduced scale,

Fig. 4 is a plan view taken in cross-section 25 on the line 4—4, Fig. 1, and

Fig. 5 is a cross-sectional view of a modification.

Referring now more in detail to the drawings, the relay of my invention comprises primarily the field magnet A and the armature B, the field magnet comprising in the form 30 shown in Figs. 1 to 4 of the drawings a field coil 10 provided with a field core having a horizontal branch 11 upon which the field coil is wound, two vertical upstanding branches 35 12, and inwardly and oppositely directed branches 13 terminating in oppositely positioned pole faces 14, the said core being preferably made of laminations of thin iron as clearly shown in Figs. 2 and 4 of the drawings, and the armature B comprising a winding or coil 15 arranged between the pole faces 40 14 of the magnet core and movable therebetween from an inactive to one or more active 45 positions, as will be described hereinafter.

As heretofore referred to, a principal object of my present invention comprehends the provision of a relay which is positive and rapid in action in response to operating influences such as are met with in service in 50 train control systems. To provide a relay possessing the desired constructional and operative characteristics, the armature which comprises the movable element of the relay is 55 constructed so as to possess little inertia, and is so mounted for movement as to be very sensitive in its action when operated. To these ends the coil 15 is wound upon a light frame 16, the said frame being rockably mounted 60 on a cradle frame 17 made of some non-magnetic material such as brass, which cradle frame is attached to the branches 13 of the field core and provided with the opposed trunnion screws 18 on which the coil frame 16 65 is journalled for oscillating movement. The

said coil 15 comprises but a few turns of wire wound on the frame 16 and connected to the lead posts 19 carried by the frame, these movable elements combinedly possessing a minimum of mass and inertia.

As heretofore referred to, another factor co-related to the production of an armature coil of low inertia for producing a relay having the desired action resides in the desirability of providing a field magnetic circuit 70 which has little reluctance, so that the magnetic field produced is correspondingly strong and of sufficient strength to cause the armature to respond rapidly to the controlling conditions. To produce a 80 magnetic circuit of low reluctance while at the same time permitting the utilization of a movable armature consisting only of the armature coil, I provide a stationary core piece 20 located within the coil 15 and stationary 85 carried by the cradle frame 17, and being attached thereto as by means of the rivets 21 (see Fig. 4), the central core piece 20 being also preferably made of laminated sheet iron as clearly shown in Fig. 2 of the 90 drawings, the said core forming part of the magnetic circuit provided by the magnet core branches 11, 12 and 13, the magnetic circuit, which includes the core branches and central core piece being substantially continuous with 95 the exception of the small air gaps between the central core piece 16 and the pole faces 14, the coil 15 being movable in these air gaps. With this construction, it will be seen that the elements comprising the entire magnetic 100 circuit are made not only to provide low reluctance, but are made stationary, none of the elements making up the magnetic circuit being movable with the armature coil, and by this means the armature coil is so inter-related 105 with the magnet field as to effect a construction in which a small inertia of the moving parts is combined with a strong magnetic field.

For supporting the field magnet and armature elements of my relay, I preferably provide a plurality, such as four, spaced brackets 110 22 which are attached to the vertical branches 12 of the magnet core as by means of the rivets 23, the field magnet A and the armature B being thus carried by the brackets; and for housing these parts of the relay, I provide a casing including the casing body 23' 115 and the casing cover 24, the brackets 22 being carried by the cover 24, the said brackets being provided to this end with the horizontal top portions 25 which are attached to the cover 24 as by means of the bolts or similar securing elements 26. The supporting brackets 22 may also be provided with the lower 120 foot portions 27 which rest upon a pad 28 provided in the casing body 23' for aiding in supporting the weight of the operating parts of the relay.

In the operation of the field and armature 130

relay parts, when either or both of the field and armature coils 10 and 15 is deenergized, the armature coil 15 assumes a neutral or inactive position in the magnetic field, as shown in the figures, and when both the field and armature coils 10 and 15 are energized, the armature coil 15 is moved to an active position for controlling operating circuits. The field coil 10 is connected by means of the 10 terminal leads 29 to binding posts 30 which are carried by the casing cover 24 as clearly shown in the drawings, and the armature winding 15 is connected to the binding posts 31 also carried by the cover 24 by means of 15 the conductors 32 leading from the binding posts 31 to the terminal posts 19 carried by the coil frame 16. Although either the coil 10 or the coil 15 may be in a deenergized state for producing the neutral position of the armature coil, in the preferred method of operation the field coil 10 is always in an energized state, the binding posts 30 being connected to an uninterrupted source of energy and the armature coil 15 is selectively energized in 20 accordance with controlling conditions, the binding posts 31 being to this end connected to the controlling circuit. With this construction it will be seen that upon selective energization of the armature coil 15 the coil 25 will be moved from its neutral or inactive position to an active position, and in the relay disclosed in Figs. 1 to 4, I show a construction in which the armature coil may be moved to one of a plurality of active positions depending upon the manner of energization 30 thereof, the said coil being movable in opposite directions for controlling different circuits when the said coil is energized in either of opposite manners.

40 For controlling the operating circuits there are provided one or more contact means controlled by the motion of the relay armature, these contact means in the preferred construction including a plurality of independent 45 contact elements each comprising a stationary contact element 32' electrically connected to a binding post such as 33 and a movable contact finger 34 electrically connected to a binding post 35, the said binding posts 33 and 35 50 being also carried by the casing cover 24 as clearly shown in the drawings, the contact elements 32' and 34 being normally out of contacting relation and being adapted to be brought into contacting relation when the 55 armature coil 15 is moved to an active position. In the construction shown in Figs. 1 to 4, I provide a plurality of sets of contact elements, one set comprising the three contact means selectively designated as J, and the other set comprising the three contact 60 means selectively designated as J', the set J being operated when the armature coil 15 is moved in one direction and the set J' being operated when the armature coil 15 is moved 65 in the opposite direction.

For operating the contact elements by movement of the armature coil 15 each of the contact fingers 34 is provided with a button 36 which is arranged for engaging the coil frame 16, the buttons 36 of set J and the buttons 36 of set J' being arranged so as to act in opposition on the coil frame 16 as clearly shown in Fig. 1 of the drawings, the construction being such that the contact fingers 34 and the buttons 36 attached thereto normally urge or bias the armature coil frame 16 and the coil thereon to the neutral or inactive position shown in the drawings. With this construction it will be apparent that when the coil 15 is energized so as to rock the 70 same in a clockwise direction as viewed in Fig. 1, the contact fingers 34 of the set J will be raised into engagement with the contact elements 32' thereof to close the circuit or circuits controlled by these contact elements, 75 and that upon energization of the armature coil 15 in the opposite direction, the said coil will be rocked in a counter-clockwise direction to raise the contact fingers 34 and buttons 36 of the set J' into contacting engagement with the contacts 32' thereof to operate the circuits controlled thereby. The relay of my construction is applicable equally 80 with direct and alternating current, and where a direct current is used a change in 85 the direction of rotation of the armature is obtained by changing the polarity of the controlling coil, and where alternating current is employed the change in direction of rotation 90 of the armature is obtained by interchanging the conductors supplying energy to the armature coil, the change in rotation being thus effected by a change in phase relation of the 95 currents in the field and armature coils.

100 In Fig. 5 of the drawings, I show a modification of my invention in which in lieu of providing a relay in which the armature is movable to any of a plurality of active positions and in which the magnet field includes an energizable field coil, a construction is provided in which the armature is movable only 105 to one active position and the magnet field comprises a permanent magnet. In this form of my invention I also provide a casing including a casing body 23'' and the casing cover 24' therefor for housing the operative 110 parts of the mechanism, the casing cover 24' being provided with one set of binding posts J, the other set of binding posts being eliminated, and carried by the cover there is provided in a manner similar to that heretofore 115 described the plurality of supporting brackets 22' which carry a permanent magnet 10' also provided with the oppositely directed branches 13' terminating in the pole 120 faces 14' between which is oscillatably movable the coil 15' wound on frame 16' and rockably mounted in the cradle frame 17', a stationary core piece 20' non-rotatably mounted 125 within the coil 15' being also provided. In 130

this form of my invention the contact fingers 34' and buttons 36' engage one side of the coil frame 16' to move the armature coil 15' to a neutral or inactive position, and for centralizing the said armature coil in neutral position there is provided an abutting member such as the screw 37 arranged for engaging the opposite side of the frame 16' to center the same as clearly shown in the figure. In this form of my invention, the armature coil 15' is normally in a deenergized state, the said coil when energized being active for effecting the closing of the contacts 34' and 32''. It will be apparent that the relay shown in Fig. 5 of the drawings may be modified by simple changes to produce a three-position relay with the employment of the permanent magnet by the addition of another set of contact elements, so that upon energization of the coil 15' in an opposite manner the other set of contacts may be operated.

The use and operation of my improved relay will in the main be apparent from the above detailed description thereof. It will be apparent that when either or both of the field and armature coils are deenergized, the armature coil will be moved to a neutral position by the contact fingers 34, and that when the armature coil is energized one or more contact means of a plurality of sets of contact means will be selectively operated, depending upon the manner of energization of the armature coil. It will be further apparent that the moving element of the relay possesses very little inertia, and is so mounted and supported as to respond sensitively and quickly to changes in the magnetic field of the relay which are of sudden and short duration corresponding to such changes as are produced by a brief period of cooperation between vehicle carried controlling circuits and roadside circuits such as are met with in the use of train control systems, the changes in the magnetic field being produced by a strong stationary field having a magnetic circuit of very little reluctance.

While I have shown my device in the preferred forms, it will be apparent that many changes and modifications may be made in the structure disclosed without departing from the spirit of the invention, defined in the following claims.

I claim:

1. A relay comprising a stationary field magnet terminating in oppositely positioned poles, an armature coil arranged between said field poles and movable when selectively energized from a neutral position in opposite

directions to either of two active positions, a stationary core within the coil forming part 60 of the magnetic circuit of said field magnet, and independent contact means controlled by movement of said armature coil to either of its active positions, the said contact means including opposing elements active on the 65 coil for biasing the same to its neutral position.

2. A relay comprising a stationary field magnet terminating in oppositely positioned poles, an armature coil arranged between said 70 field poles and movable when selectively energized from a neutral position in opposite directions to either of two active positions, and independent contact means controlled by movement of said armature coil to either of 75 its active positions, said contact means including resilient contact elements oppositely active on the said armature coil for biasing the same to its neutral position.

3. A relay comprising a stationary field 80 magnet terminating in oppositely positioned poles, an armature coil arranged between said field poles and movable from a neutral to an active position, a stationary core within the coil forming part of the magnetic circuit of 85 said field magnet, and a plurality of contact means spaced longitudinally of and controlled by the movement of said armature coil, each of said contact means comprising a stationary contact element and a resilient 90 movable contact element engaging said coil and active for biasing said coil to its neutral position.

4. A relay comprising a stationary field magnet terminating in oppositely positioned 95 poles, an armature coil arranged between said field poles and movable when selectively energized from a neutral position in opposite directions to either of the two active positions, a plurality of pairs of contact means 100 controlled by the movement of said armature coil to either of its active positions, the contact means of each pair being arranged on opposite sides of said coil and the pairs being spaced longitudinally of said coil, each 105 of said contact means comprising a stationary contact element and a movable resilient contact element engaging the armature coil for biasing the same to its neutral position, the movable contact elements of a pair of 110 contact means being arranged to act in opposite.

Signed at Chicago, in the county of Cook and State of Illinois, this 9th day of November, A. D. 1922.

CARL G. HARWIG.
